UNITED STATES PATENT OFFICE.

JAMES HENRY MINER, OF LUMBERTON, MISSISSIPPI.

SAW.

SPECIFICATION forming part of Letters Patent No. 784,113, dated March 7, 1905.

Application filed May 4, 1904. Serial No. 206,380.

To all whom it may concern:

Be it known that I, JAMES HENRY MINER, a citizen of the United States, residing at Lumberton, Mississippi, have invented certain new and useful Improvements in Saws, of which the following is a specification.

My invention relates to improvements in saws, and more particularly to that class of saw embodying in its construction removable and interchangeable teeth.

I have aimed to provide means which may be readily applied to the saw to prevent the wearing of the throat of the tooth which will prevent the tension of the saw being changed by obviating wear at the edge of the saw, and I have also aimed to so construct said means as to avoid unnecessary fastening devices and make replacement easy and inexpensive.

The invention is illustrated in the accompanying drawings, in which—

Figure 1 is a side view of a sufficient portion of a saw to illustrate the invention, and Fig. 2 is a sectional detail view.

In the drawings, the ordinal 3 indicates the body of the saw, and 4 the removable teeth. These may be retained in the tooth-sockets in any desired manner—as, for instance, by a locking pin or key 5; but as this forms no

part of the present invention a more detailed description is deemed unnecessary.

The ordinal 6 indicates a lining-spring which extends, as shown, around the throat of the tooth and protects it from wear. The forward end 7 is flush with the back edge of the tooth-body, and I have found that each spring 35 may be held in a simple and effective manner by providing an overhanging lug or projection 8, which clamps the spring firmly against the throat.

Having thus described my invention, what I claim is—

In a changeable-tooth saw, the combination with the tooth, a projection from the body of the saw, a lining plate or spring encircling the throat of the saw and one end of said lining-spring passing over the projection on said saw, of a hook-shaped projection on said tooth overhanging the end of said lining-spring and retaining the same in place, substantially as described.

In testimony whereof I affix my signature in presence of two witnesses.

JAMES HENRY MINER.
